UNITED STATES PATENT OFFICE.

WILLIAM H. ISBISTER, OF PHILADELPHIA, PENNSYLVANIA.

DESIGN FOR AN ORNAMENTAL ALBUM-COVER.

SPECIFICATION forming part of Design No. 29,258, dated August 23, 1898.

Application filed July 16, 1898. Serial-No. 686,156. Term of patent 7 years.

To all whom it may concern:

Be it known that I, WILLIAM H. ISBISTER, a citizen of the United States, residing in the city of Philadelphia, State of Pennsylvania, have invented and produced a certain new and original Design for Ornamental Album-Covers, of which the following is a full, clear, and exact description, reference being had to the accompanying drawings, forming a part 5 of this specification.

My invention relates to ornamental album-covers; and it consists in the novel form and configuration thereof, substantially as shown in the accompanying drawings, in which—

15 Figure 1 shows the ornamental mounting applied to a plush album-cover, a mirror (for illustration) being shown as held in place within the inwardly-curved edges or flanges of the open center. Fig. 2 is a section through 20 the vertical center of the mounting.

The design, as shown, consists in a book-cover upon which is secured a mounting the frame of which has the general form of the Liberty Bell. The inner edge of the central opening in the frame is flanged or curved 25 downward and inward, and the body portion is raised above the plane of the edges, as shown in Fig. 2, in what may be called "alto-relievo."

What I claim is—

30 The design for an ornamental album-cover, substantially as shown and described.

In testimony whereof I have hereunto affixed my signature this 11th day of July, A. D. 1898.

WILLIAM H. ISBISTER.
